DESIGN FOR A GLOVE

Louis Levine, New York, N. Y., assignor to Van Raalte Company, Inc., New York, N. Y., a corporation of New York

Application November 27, 1935, Serial No. 59,795

Term of patent 3½ years

To all whom it may concern:

Be it known that I, Louis Levine, a citizen of the United States, residing at New York, county and State of New York, have invented a new, original, and ornamental Design for a Glove, of which the following is a specification, reference being had to the accompanying drawing, forming a part thereof.

The entire glove, with the exception of the strap-like wrist-band, is of the same fabric, the texture of which is indicated in detail at several points on the glove. The glove is characterized by the braided cord cuff brought together by a faceted button.

I claim:

The ornamental design for a glove, as shown and described.

LOUIS LEVINE.
